OIL-ENGINE.

1,070,333.

Specification of Letters Patent. Patented Aug. 12, 1913

Application filed June 24, 1910. Serial No. 568,654.

To all whom it may concern:

Be it known that I, ALESSANDRO FRANCHETTI, a subject of the King of Italy, and a resident of New Rochelle, in the county of 5 Westchester and State of New York, have invented certain new and useful improvements in Oil-Engines, of which the following is a full, true, and concise specification.

This invention is an internal-combustion, 10 oil engine, being an improvement in that general type of engines in which a liquid fuel is injected into a body of previously compressed fresh air confined in a combustion space or chamber wherein the expansion, due to the combustion, imparts motion to the engine piston. Its object is increased efficiency in the process of converting fuel energy into useful work, and such object is obtained by the arrangement and combination, 15 of the engine parts hereinafter described and pointed out in the claims, and more particularly by the shape and disposition of the combustion chamber, and the relation to such chamber, and the coöperation therewith, of its several valves and igniter and the means and method of injecting the fuel, whereby the combustion is caused to take place progressively from one end of the chamber to the other, with superior pressure 20 effect, as will be later described.

The invention further involves improvement in the facility for regulation and automatic control, an enlargement of the range of grades of fuel oil which can be satisfactorily used, the capacity for manufacture at relatively low cost and weight per horse power delivered, and also the adaptability of construction, without diminishment of the efficiency ratio, to engines of extremely 25 large sizes, all of which will be plain to those skilled in this art from the following description, and the drawings forming a part thereof.

The invention still further includes certain features of structural formation, appearing in the specific engine taken for illustration and shown in the said drawings and which are likewise included in the claims, though it will be understood by those skilled 30 in this art that the invention may be embodied in engines widely differing in their mechanical design.

Figure 1 represents a plan view of a horizontal engine, embodying my invention and constructed to operate on a four-stroke

cycle; Fig. 2 is a vertical longitudinal section of the same engine; Fig. 3 is an end elevation, with a portion of the cylinder head broken out and the interior shown in vertical section on the plane of the valve-stems; Fig. 4 is an elevation, in enlarged scale, of the valve gearing and the oil pump with the cam shaft in transverse section on line IV—IV of Fig. 1; Fig. 5 is a side elevation of the same parts; Fig. 6 is an enlarged longitudinal section of the fuel injecting mechanism; Fig. 7 is a cross-section of the fuel valve chamber thereof through the supply ducts; and Fig. 8 is a detail of the fuel subdividing device.

The engine comprises the usual water-cooled cylinder 1 and piston 2, connected in the usual manner with the crank shaft 3 and fly-wheel, all of which parts are carried on a suitable base, as will be well understood. The air and exhaust valves, and the fuel valve and ignition means are all contained in the cylinder-head of the engine and are relatively arranged therein in radial positions and in the same plane, which plane is preferably transverse to the longitudinal axis of the engine, and, in the present case, vertical. The space between these several parts provides the compression and combustion chamber of the engine, being in communication with the cylinder proper through a short and relatively narrow passage 4 which opens laterally from the chamber, as shown in Fig. 2, with its walls diverging toward the cylinder and meeting the circular end of the jacketed wall thereof. The face of the working piston is forwardly tapered, corresponding to the divergence of the passage or opening 4, and is adapted to occupy and substantially fill the whole of 50 said space when in its forward dead center position, so that practically all the contents of the cylinder will be pushed into the combustion chamber when the piston reaches the end of its stroke. The extreme forward end 55 of the tapered piston, which is provided with a protuberance 2^a, will then form a portion, though not a large portion, of the inclosing boundary of the combustion chamber. The separation of the combustion chamber from the cylinder by this short and relatively narrow passage, filled and closed by the piston end, facilitates its construction with the shape and size which 60 specially contributes to the improvements

gained by this invention, the chamber being longer than it is broad and preferably of greater cross section at one end than at the other. It is to be noted, however, that while the said restricted passage 4 constitutes a 5 desirable feature of the preferred embodiment of this invention, it is not essential to the production of the chamber shape just referred to.

10 The air intake passage 5 and its air valve 6 occupy the upper portion of the cylinder-head, the said passage and the valve chamber thereof being water-cooled as shown, and the exhaust passage 7 and exhaust valve 8 occupy the lower portion of the cylinder-head, being also similarly water-cooled. Both of 15 these valves are desirably puppet valves with their flat heads disposed in opposition to each other on opposite sides of the major axis of the chamber, and also preferably on opposite sides of the axis of the opening 4, so that they form symmetrically located and further portions of the boundary wall of the combustion chamber. Directly opposite 20 the passage 4, the cylinder-head is equipped with a starting valve 60 of ordinary and obvious construction, which is supplied with pressure through a pipe 61 and operated by a handle 62, whereby the pressure medium 25 can be admitted into the interior of the cylinder for starting the engine from a state of rest. It will be observed that the end 2^a of 30 the piston and the foregoing valves, being thus located at or around the junction of the axis of the piston and the major axis of the 35 combustion chamber determine the cross-section of the combustion chamber at this point, forming an intermediate portion of the said chamber.

40 The fuel injecting mechanism, designated generally by the numeral 9, is located at one end of the combustion chamber, as shown in Fig. 3. Its principal function is to inject the fuel into the chamber, forcibly and in a 45 state of extremely fine subdivision or atomization and preferably mixed with air, as later explained. It is so located that the blast of atomized fuel particles issuing from its nozzle, is projected centrally through the 50 length of the chamber and through the intervalvular junction space just referred to. The boundary walls of the combustion chamber diverge from the nozzle end of the fuel valve until they meet the cross-section of 55 the junction space and continue, divergently, beyond this space, meeting the unjacketed wall 10, formed by a bulbous extension removably secured to the cylinder-head as shown in Fig. 3, forming an end closure to 60 the chamber in direct opposition to the fuel valve nozzle. The shape of the combustion chamber is substantially symmetrical with respect to its major axis, being proportioned to correspond closely to the shape of the 65 blast of entrained air and atomized fuel

which issues from the fuel valve, thereby making every part thereof directly accessible to the particles of the blast, so that the whole of the charge of compressed air therein will be penetrated by and thoroughly permeated with the finely atomized fuel particles. The shape of the chamber thus resembles that of a somewhat elongated pear, with the fuel admission nozzle at, and constituting the smaller end, and the opposite unjacketed wall 10 constituting the fundus thereof at the other. In operation, this unjacketed end wall is kept hot by the combustion taking place inside the chamber, as will be well understood, and thus forms a hot-surface igniter, the area of which is sufficient to receive the entire impingement of the blast, while the portions of the boundary wall of the chamber intermediate of the igniter and the fuel valve are maintained at a lower temperature, less than the ignition of the fuel, by virtue of the surrounding water jacket and the continual contact which these parts have with fresh air coming in through the air-intake valve 6. The unjacketed wall or bulb 10 may be formed with a smooth interior surface, as shown, or it may be ribbed or corrugated to increase its surface area and it will be understood that it requires to be initially heated on starting the engine 95 after a period of rest.

With the proportions of the combustion chamber thus made to conform to the shape of the fuel blast, its general dimensions are selected with reference to the stroke-volume of the working piston to produce a compression pressure of the air charge therein of about 300 lbs. per sq. in., but susceptible of variation in either direction as desired, the compression being in any event lower than will produce a temperature of the air charge equal to the ignition temperature of the fuel and likewise considerably higher than that which is used in engines of the type wherein the mixture of the fuel and air is first made, then compressed and subsequently positively ignited by flame or spark, such, for instance, as the ordinary gasoline engine; it is a prominent characteristic of the present invention that the compression pressure employed is intermediate between this well known type of engine and the high pressure type wherein the compression temperature serves to ignite the fuel. The permissible range of compressions may be stated to be from 150 to 450 lbs. per sq. in., being preferably about 300 lbs., as above given. By removing the igniter bulb and substituting others of different sizes or shapes, the compression pressure may be varied to such extent within the limits stated, as may be deemed advisable.

The introduction of the fuel in the form of a forcible blast or spray of finely divided or atomized fuel particles which occupies

substantially the whole cross-section of the chamber, as above explained, results in two separate effects or stages in the working process of the engine. The first of these is 5 the rapid and almost instantaneous preparation of a mixture of the fuel with the charge of compressed fresh air confined in the chamber, and is produced by the commingling therewith of the finer particles of 10 the atomized blast which have not sufficient momentum to overcome the resistance encountered in their lengthwise traverse through the oblong body of compressed air. These particles consequently become caught 15 and remain suspended therein, forming an effective combustible mixture. The other and immediately succeeding effect is the actual ignition of this mixture, which takes place only when the larger particles, by 20 reason of their superior momentum, have reached and impinged upon the hot igniter plate at the end of the chamber and become ignited by their contact therewith, inflaming the mixture. Ignition of each fuel charge 25 is thus compelled to take place subsequently to the formation in whole or in part, of the combustible mixture and the combustion of the latter starts at the igniting end of the chamber and progresses backward toward 30 the fuel valve, in the reverse direction to the entry of the fuel blast, expanding the meantime and imparting motion to the piston, as will be well understood. It may be explained that the pressure effect thus produced 35 closely resembles that of engines of the ordinary gas-engine type wherein the combustible mixture is made first, then compressed, and then positively ignited, and the resulting pressure diagram is the characteristic 40 and efficient diagram of that type of engine, notwithstanding that the fuel is introduced when the compression of air has been practically completed and that it may consist of the heaviest grade of fuel oils 45 which would be quite impossible to be used in the ordinary gasoline engine. The mode of mixture formation and ignition provides uniformly efficient combustion of heavy oil at low compression, which permits the engine 50 parts to be made of light construction as compared with high compression engines heretofore employed for similar grades of fuel.

The introduction of fuel takes place after 55 the compression stroke has been completed and at or about the compression dead-center of the working piston, being preferably so timed as to take place, in whole or in part, somewhat prior to the dead-center point, the period 60 of introduction being in any event as brief as consistent with the mechanical construction of the parts which move the fuel.

The fuel injecting mechanism 9 utilizes 65 compressed air for atomizing the charge of fuel oil, and projecting it with the required

velocity into the combustion chamber. The air for this purpose is supplied through a pipe 11 (Fig. 3) leading from the air compressor 12 and the oil through a pipe 13 from an oil pump 14 (see Fig. 3), and it 70 will be understood that the pressure on both the oil and air is in excess of the compression pressure of the engine so that a forcible fuel blast, as above explained, will be produced. The air and oil from their respective pipes 11 and 13 enter the main casing 15 of the fuel injection mechanism through the two ducts therein marked 16 and shown in Figs. 6 and 7. This casing constitutes the valve chamber of the fuel valve, and provides the space in which the air and oil are subdivided and commingled preparatory to admission to the combustion chamber. It is seated in a recess or lateral opening of 75 the water-jacketed wall of the cylinder head, 80 with its discharge nozzle entering the smaller end of the combustion chamber and lying coaxially with the major axis thereof at a point which is thus most remote from the igniting surface 10. While the nozzle of 85 the casing may be formed in one piece therewith, it is shown as made in the form of a removable nipple 17, one end of which forms the valve seat for the valve plug 18, the latter being the fuel valve and being normally 90 held upon its seat on the nipple by the pressure exerted by its seating spring. The communication between the valve chamber and the combustion chamber is thus maintained closed except such time as the fuel 95 blast is being admitted to the combustion chamber. The valve plug 18 is surrounded by a sleeve or barrel within the valve chamber in which it has a sliding fit and which constitutes a means for mechanically breaking up and subdividing the fuel charge. The exterior of this barrel is formed with a series 100 of enlargements or collars 19 fitting the interior of the casing 15 rather snugly and superficially scored with numerous fine intersecting grooves resembling nurling, as shown more clearly in Fig. 8.

The oil and air under the high pressure imparted by their respective compressor mechanisms enter from the pipes 11 and 13 115 respectively into the annular space between the outer surface of the barrel or mixing device 19 and the inner surface of the valve casing 15 and when the fuel valve 18 is opened by removal from its contact with the 120 nozzle 17, the oil and air are compelled to pass through the fine intersecting grooves on the faces of the collars 19; in so passing the oil becomes thoroughly broken up into subdivided particles and thoroughly inter- 125 commingled and atomized with the air, this mixing operation taking place outside of the combustion chamber of the engine and in advance of the entrance of the fuel thereto. A dust-like and homogeneous blast of oil 130

particles is thus produced, which is particularly well adapted for the instantaneous formation of combustible mixture in the combustion chamber, in the manner above explained, though other means for producing such blast might be provided with equal effect. The principle above explained is substantially the same as described in my Patent No. 857,566, dated June 18, 1907. The stem 10 of the fuel valve 18 extends to the exterior of the valve chamber, through the gland 20 at the end of the latter, where it is supplied with its seating spring 21 and its operating connections. The extreme end of the stem 15 is threaded and carries an adjustable abutment in the form of the nut and lock-nut 22, the former of which is adapted to be engaged by a sleeve 23, subject to operation by the short actuation lever 24, so that the appropriate movement of the latter will withdraw the valve plug from its seat against the pressure of the spring and open the communication between the valve chamber and the combustion chamber. The several parts 20 of the fuel injecting mechanism are carried by the exterior casing 15^a which is placed over the end of the casing 15 of the valve chamber and is then bolted by the bolts shown, to the cylinder head, clamping the 25 said casing firmly in its seat in the latter.

The compressor 12 for the atomizing air is located at one side of the engine cylinder, being secured to the cylinder casting as shown in Fig. 1, and operated by a connecting rod 25 from an eccentric on the crank-shaft 3. The atomizing air is desirably compressed in two stages to the pressure desired, and the two-stage apparatus shown, comprises two water-jacketed compressing cylinders 26 and 27 formed in a single casting in tandem relation, and provided with compressing plungers correspondingly arranged and connected to the eccentric rod 25. Air admitted through the intake pipe 28 to the 30 larger and low compression cylinder 26 is compressed through pipe 29 into the low pressure storage tank 30. From this tank it is admitted, through pipe 31, into the high compression cylinder 27, wherein it is further compressed through suitable valves and an air dome 32, into the fuel-air pipe 11 above referred to. The oil pump 14 is located on the opposite side of the engine, being carried on the extension bracket 33, 34 secured to the side of the cylinder head for supporting the governor 35 and the journal seat of cam shaft 36. Oil is supplied to the pump through the feed-pipe 37 and forced through the oil pipe 13 into the chamber of 35 the fuel valve against the pressure of the atomizing air therein, the amount of oil delivered being regulated in any suitable way, as for instance by varying the length of stroke of the pumping plunger under the 40 control of the engine governor, so that a pre-

determined quantity of oil constituting the appropriate fuel charge will be caused to pass through the pipe 13 into the chamber of the fuel valve. In the present case the oil pump is driven by a bell crank 38, jointed to the pumping plunger and operated through a shifting, governor-controlled transmission bearing 39, by a cam-lever 40 which is oscillated by a cam 41 on the extreme forward end of the cam shaft 36. The operated arm of the bell crank and the free arm of the cam lever 40 extend in opposite directions from their respective fulcras, and toward each other, as shown in Fig. 3, so that they mutually overlap for a considerable portion of the length of each. The transmission bearing 39 is in the form of a roller carried on a yoke 42, and is interposed between the two levers so as to transmit the motion of the cam lever to the bell-crank and thence to the plunger. The yoke is pivotally suspended by an adjustable rod 43 from the end of the governor lever 44, so that the position of the bearing roller will be varied by change in speed of the 45 governor, and will thereby vary the active lengths of the two levers and produce a longer or shorter pumping stroke, as may happen to be required. Under normal load the bearing will occupy an intermediate 50 position and the stroke of the plunger will force a suitable normal charge into the valve chamber. Variation in the load and the resulting change in speed of the governor will produce a corresponding shifting of 55 the transmission bearing, relatively to the levers, and a corresponding adjustment of the measured charge of oil. The governor 35 is driven from the cam shaft 36, and the latter is driven from the crank shaft, the 60 driving gearing in each case being inclosed within gear casings which conceal them from view in the drawings. The casing of the governor gears is marked 45 and is applied to the end of the bracket support 65 34 within which the gears and governor spindle are journaled, as will be well understood by engine builders.

Referring now to the gearing by which the several valves of the engine are actuated, a separate operating cam is supplied for each valve, all of them being mounted side by side and at one end of the cam shaft 36, with their respective connections suitably offset so as to be made effective in the same 70 transverse plane as the plane of the valves. The first of these valve-controlling cams is located immediately in the rear of the bracket 34, being the fuel controlling cam and marked 50 (Figs. 4 and 5). This cam 75 engages a bell crank lever 51 pivoted to the rear face of the bracket 34 and connected by a link 52 (Figs. 4 and 6) with the short actuating lever 24 of the fuel valve, which has been described above. The contour of the 80

fuel cam produces a positive oscillation of these valve-actuating connections, giving a quick opening and closing of the fuel valve 18. The second cam, 53, next in line on 5 the cam shaft 36, operates the exhaust valve 8 through its cam-lever 54, which is pivoted at 55 on a suitable depending portion of the side bracket 34 and engages the lower side of the cam, with its other end directly 10 engaged with the downwardly extending and spring-pressed stem of the exhaust valve 8. The third cam, 56, actuates, on its lower side, a bell crank lever 57 fulcrumed on a stud 58 and jointed to a connecting rod 59. The arms of said rocking 15 lever are offset so that the rod 59 may occupy the same plane as the several valves, and on this account the said rod is branched or split where it passes the fuel injecting 20 mechanism 9 so as to accommodate that valve without interference with its operating connections above described. The upper extremity of the connecting rod 59 is connected to a rocking lever 59^a directly 25 engaging the stem of the air intake valve 6. This valve and also the exhaust and fuel valves, are supplied with closing or seating springs sufficiently powerful to maintain their respective cam-levers in working 30 contact with their corresponding cams.

In starting the engine from a state of rest, the igniter wall, having been first heated, a charge of fuel oil is introduced by hand into the valve chamber of the fuel valve, 35 for which purpose the bell crank 38, above described, is supplied with a hand lever 63 by means of which it can be manually operated. Compressed air is thereupon admitted to the combustion space through the 40 starting valve 60 and the fuel injected to produce a first explosion. In the succeeding operation, a charge of fresh air is drawn in through the air valve 6, mechanically opened for the purpose, and is com- 45 pressed in the combustion chamber. About the dead center point or preferably some- what in advance thereof, the fuel valve is opened and the pulverized blast of oil and air shoots through the chamber, first pro- 50 ducing the combustible mixture as above explained and subsequently the ignition fol- lowed by the combustion and expansion, against the piston, imparting to the latter its working stroke. During the return 55 stroke, the piston scavenges the cylinder of the products of combustion, forcing them out through the exhaust valve 8, opened by the exhaust cam 53, and on the succeeding suction stroke a fresh charge of air is taken 60 in through the air valve 6 and compressed as before, and so on, as will be well under- stood.

It will be observed by those skilled in this art that the manner of injecting the fuel 65 and mixing the same with the compressed

air and igniting the mixture as herein described, is independent of the cycle under which the engine is constructed to run, and it will be understood that while a four-cycle engine has been herein shown and de- 70 scribed, as illustrative of the principle of the invention, the invention is not limited thereto, and that numerous changes and alterations in the design and construction of the engine and in the mode of compressing or introducing the air and injecting and controlling the fuel oil and also in the ar- 75 rangement of any of the operating means, may be made within the scope of the appended claims and without departing from the in- 80 vention. It will also be understood that the air valve 6 may be of the lift-valve-type and operated by the pressure of the air, instead of by means of mechanical devices, for that purpose, and that various other 85 modifications can be made within the invention.

I claim:—

1. An oil engine of the class described comprising a piston and cylinder and a 90 combustion chamber, said chamber being relatively long and of greater cross-sectional area at one end than at the other, its terminal wall at the larger end being adapted to be kept at an igniting temperature by the 95 heat of combustion, means for filling the chamber with a charge of compressed fresh air, a fuel-injecting valve arranged to project a fuel blast through the length of such chamber to be ignited by contact with the 100 terminal wall and means for operating such valve when the chamber is filled with the compressed air.

2. An oil engine of the class described, comprising a cylinder having a combus- 105 tion chamber of greater length than breadth and means for filling said chamber with a charge of compressed fresh air, a fuel valve at one end of said chamber, arranged to project a blast of finely-divided fuel-oil 110 through the length of said chamber from end to end thereof and functioned to operate during the confinement of the said air charge therein, the boundary wall of said chamber at the middle and at the fuel valve 115 end being water-jacketed and the terminal wall at the opposite end being unjacketed, whereby combustion is caused to take place at said terminal wall and progress toward the fuel valve.

3. An oil engine having a combustion chamber of greater length than breadth and a piston adapted to compress a charge of compressed fresh air therein, a hot-surface igniter forming the boundary wall of said chamber at one end thereof, and a fuel valve nozzle disposed in said chamber at a point 125 therein most remote from said surface igniter, in combination with means for atomizing liquid fuel with air and forcing such 130

- atomized fuel through said nozzle and the compressed fresh air charge, and against said igniting surface.
4. An oil engine of the class described having a working cylinder and a combustion chamber longer than it is broad or wide, symmetrically disposed about its major axis and of larger cross-section at one end than at the other whereby the walls of said chamber substantially conform to shape of the fuel blast, the terminal wall at the larger end of said chamber forming a surface igniter, in combination with a nozzle at the smaller end of the chamber provided with means adapting it to project an oil dust blast of mixed fuel-oil and air through said chamber and against said surface igniter, means for introducing fresh air to said chamber and a working piston for holding the same therein under pressure and subject to penetration by said blast.
5. An oil engine having a combustion chamber longer than it is broad or wide and provided with a fuel nozzle at one end and means for igniting the fuel at the other, and with air-intake and exhaust valves intermediate of said parts, in combination with the engine piston operating to confine a charge of compressed fresh air in said chamber and means for projecting a finely divided fuel blast from said nozzle into and through the compressed charge of air in said chamber.
6. In an oil engine, a cylinder and a combustion chamber of greater length than breadth adapted to contain a charge of compressed fresh air and provided with a surface igniter forming the terminal wall at one end, a fuel blast device at the opposite end, in combination with air and exhaust valves forming portions of the lateral boundary wall of said chamber between said parts, a passage between said parts connecting with the cylinder, and a piston in the latter adapted to close said passage and form a further portion of the boundary of said chamber.
7. An oil engine having a combustion chamber longer than it is broad or wide and of greater cross-section at one end than at the other and provided with a valved air entrance in its wall and a piston for taking air into the chamber through said entrance and adapted for compressing such air thereinto to a temperature less than the ignition temperature of the fuel, the wall of the said chamber at its larger end being unjacketed and constituting an igniting surface, in combination with a fuel injector at the smaller end of the combustion chamber and means timed to operate said injector to project a blast of atomized fuel oil through the compressed air charge and against the said igniter surface.
8. An oil engine of the class described having means for projecting the fuel oil in a blast of finely divided dust-like particles and a combination chamber conforming to the shape of said blast and having an unjacketed wall to receive the impingement thereof centrally disposed with respect to the axis of the blast, in combination with the working piston and a suitable air-inlet port arranged for filling said chamber with a charge of compressed fresh air and means for timing the fuel-oil blast so that it will penetrate the entire body of said charge and impinge upon the said unjacketed wall.
9. An oil engine of the class described provided with a combustion chamber and means for admitting fresh air thereto and having its piston related thereto to compress the same therein, a portion of the wall of said chamber being unjacketed and constituting a surface igniter, in combination with means comprising a casing for mixing fuel-oil and air and having a passage communicating between the casing and the chamber at a point in the latter opposite the said unjacketed wall, a fuel valve closing such passage during the outward stroke and the greater part of the compression stroke of the piston and means for opening said valve at or about the end of the compression stroke.
10. An oil engine comprising a combustion chamber with a portion of the wall thereof unjacketed and provided with an air admission passage and a working piston arranged to compress a charge of air in said chamber, in combination with a fuel injecting mechanism comprising a casing communicating with said chamber at a point therein which is most remote from said unjacketed wall, a valve normally closing the communication between the chamber and said mechanism, means for supplying liquid fuel and atomizing air to said casing and means for opening said valve at or about compression dead center.
11. An oil engine having a combustion chamber of greater cross-sectional area at one end than at the other and provided with means for allowing fresh air to pass into said chamber and having an unjacketed wall at one end therof and fuel atomizing mechanism at the other, and a piston operating to compress a charge of fresh air into said chamber, in combination with a valve-controlled communication between said chamber and fuel atomizing mechanism and means for opening the valve thereof to inject the fuel through the charge of compressed air in said chamber and against the opposite unjacketed wall thereof.
12. An oil engine having a combustion chamber longer than it is wide and having an igniter formed by an unjacketed terminal wall of said chamber at its end of longest dimension, and means including the work-

ing piston for confining a compressed air charge in said chamber, in combination with fuel injecting mechanism at the opposite end of said chamber comprising a casing and a fuel valve controlling the communication between said chamber and casing means for delivering oil and air to the casing at a pressure in excess of the compression pressure in the chamber, and means 10 for opening said fuel valve during the compression stroke of the piston.

13. In an oil engine, a cylinder and piston adapted to compress a charge of fresh air and provided with a combustion chamber for confining such air having a portion of its wall unjacketed and providing a hot surface igniter, fuel injecting mechanism for said chamber comprising a casing having communication with a source of air pressure higher than the compression pressure in said chamber, means for delivering into said casing a charge of liquid fuel and a fuel and air mixing device in said casing, in combination with a valve closing the communication between said casing and the combustion chamber and means for opening said valve at or about the end of the compression stroke of the piston.

14. In an oil engine, the combination of the piston and cylinder thereof arranged to receive and compress a charge of fresh air and provided with a combustion chamber for confining said compressed charge of greater length than breadth and symmetrically disposed about its longitudinal axis thereby adapting every part of said chamber to be directly reached by a blast issuing from a point at one end thereof, said chamber having its wall, opposite said blast, unjacketed and forming an igniter surface, fuel injecting mechanism adapted to project an atomized spray of fuel oil into said chamber and comprising a casing in normal communication with a source of air of higher pressure than the air in said chamber, means for delivering fuel into said casing, a valve closing the communication between said casing and combustion chamber and means for opening said valve at or about the compression dead center.

15. In an oil engine, a piston and cylinder arranged to compress a charge of fresh air and provided with a combustion chamber for confining such compressed charge, and opposed air intake and exhaust valves disposed respectively on opposite sides of said combustion chamber, in combination with fuel-blast-producing mechanism operative to inject a spray of finely-divided fuel into said compressed charge and between said opposed valves, said chamber having the portion of its wall opposite said fuel mechanism unjacketed and constituting a surface igniter for said fuel.

16. In an oil engine, a piston and cylinder

arranged to compress a charge of fresh air to a pressure less than the ignition temperature of the fuel and having a combustion chamber substantially conforming to the shape of the fuel blast, the end wall thereof being unjacketed, in combination with opposed air intake and exhaust valves respectively disposed on opposite sides of the middle part of said chamber, a fuel injecting device located at the smaller end of said chamber and operative to direct fuel in atomized condition between said valves and against the end wall, a valve controlling the communication between said injecting device and the combustion chamber and means for opening the same.

17. An oil engine having a combustion chamber of greater length than breadth and its working cylinder in communication with said chamber through a relatively narrow passage, the axis of which intersects the major axis of said chamber, in combination with an air intake valve on one side of the intersection thereof and an exhaust valve on the other and means for projecting a fuel blast through the space between said valves.

18. In an oil engine of the class described, the combination with the working cylinder and a combustion chamber communicating therewith, having greater length than breadth, of opposed air intake and exhaust valves forming portions of the wall of said chamber on opposite sides of the junction thereof with the cylinder and means for projecting a fuel blast between the said opposed valves.

19. In an oil engine of the class described, the combination with a combustion chamber of greater length than breadth, and having larger cross-sectional size at one end than at the other, of air intake and exhaust valves forming portions of the boundary wall of said chamber between its larger and smaller ends, an igniting surface at the larger end and means for directing a fuel blast against said igniting surface.

20. An oil engine having a portion of the combustion chamber wall thereof unjacketed, fuel injecting mechanism opposed to said wall and suitable valves for admitting air and venting the exhaust, all disposed in a plane transverse to the working piston and having a starting valve entering the head of the engine at an angle to said transverse plane.

21. In an oil engine, a cylinder and a cylinder-head having a transversely disposed combustion chamber provided with fuel injecting mechanism and valves for admitting air and venting the exhaust with their several axes radially arranged with respect to said chamber, in combination with an unjacketed portion of said cylinder-head forming the wall of said chamber opposite the fuel-injecting mechanism.

22. In an oil engine, a cylinder and a cylinder-head having a transversely disposed fuel injecting nozzle and an unjacketed portion of said head arranged in opposition thereto, in combination with air intake and exhaust valves in said head disposed on either side of the discharge from said fuel nozzle, and between the said nozzle and said unjacketed portion.
23. In an oil engine having its air intake and exhaust valves disposed in opposition to each other and operable in a vertical direction to admit air to the combustion space and to exhaust the combustion products therefrom, the combination with a horizontally-disposed fuel nozzle, a fuel valve normally closing the same, means for supplying air and oil thereto under pressure, and unjacketed portion of the engine wall disposed in opposition to and receiving the impingement of the spray injected thereby and means for opening said valve at or about compression dead center.
24. In an oil engine, a cylinder having a passageway of less diameter leading therefrom and a piston in said cylinder having its forward end reduced in diameter to correspond therewith and adapted to compress all the air in said cylinder into and through said passage, a transversely arranged combustion chamber of greater length than breadth, arranged to receive and confine such compressed air and provided with opposed surface igniter and fuel-blast producing device, and air intake and exhaust valves, forming portions of the wall of said chamber intermediate of said igniter and fuel blast device.
25. In an internal combustion oil engine, the cylinder having an open passage at its forward end and provided with a combustion chamber in communication with said passage, air intake and exhaust valves for said chamber respectively disposed on opposite sides of the axis of said passage, a fuel blast device disposed transversely to said axis and an unjacketed wall of said chamber disposed opposite to said injector, in combination with a piston coöoperating with the aforesaid parts to compress a charge of
- fresh air in said chamber and means for operating said fuel blast device during the compression of said charge.
26. In an oil engine of the class described, the combination with the cylinder of a cylinder head having the fuel valve and air and exhaust valves all contained therein and relatively arranged with their axes in radial positions and in the same plane, of the engine piston arranged to compress a charge of fresh air into said cylinder head, means for operating the fuel valve at or about compression dead center and an unjacketed wall opposite said fuel valve.
27. The combination in an oil engine of the class described, of a cylinder and cylinder head containing a combustion chamber with an unjacketed wall and provided with a passage leading from the chamber to the cylinder with diverging walls which meet the circular end of the cylinder, a tapered piston conforming to and adapted to fill the space within said diverging walls, air and exhaust valves and a fuel valve in the cylinder head communicating with said combustion chamber and means for operating said fuel valve at or about compression dead center.
28. In an internal combustion oil engine, the combination with a combustion chamber of greater length than breadth disposed with its major axis transverse to the axis of the engine cylinder and having a relatively small cross-sectional area at one end, and means for establishing a body of compressed fresh air therein, of a fuel injection valve communicating with the small end of the chamber to discharge an atomized spray of oil and air thereinto, and an unjacketed portion of the chamber wall forming the closure to the opposite and larger end of said combustion chamber.

In testimony whereof, I have signed this specification in the presence of two witnesses.

ALESSANDRO FRANCHETTI.
